STORM UMBRELLA

Ovaldo Wendorf, 325 Broadway, Newark, N.J.
Filed Mar. 1, 1961, Ser. No. 92,585
7 Claims. (Cl. 135—35)

This invention concerns an improved umbrella.

According to the invention there is provided a collapsible type umbrella provided with air vents which permit release of air pressure in a high wind. In addition a plurality of guy members are connected between ends of the ribs and the central umbrella post to prevent the umbrella from turning inside out in a high wind. The guy members may be flexible cords, chains, or the like.

It is therefore one object of the invention to provide an improved umbrella provided with air pressure release vents and with guy members to prevent the umbrella from turning inside out.

A further object is to provide a collapsible umbrella with a plurality of guys connected between the central post and ends of the ribs of the umbrella.

Another object is to provide an umbrella with flexible and quickly mountable guys for reinforcing the frame thereof and preventing the umbrella from turning inside out.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

FIG. 1 is an elevational view of an umbrella according to the invention.

FIG. 2 is a top plan view on a reduced scale of the umbrella of FIG. 1.

FIG. 3 is an elevational view of the umbrella in closed position.

FIG. 4 is a sectional view on an enlarged scale taken on line 4—4 of FIG. 2.

FIG. 5 is a sectional view on a reduced scale taken on line 5—5 of FIG. 4.

FIG. 6 is a fragmentary perspective view of part of the guy mounting assembly.

FIG. 7 is a bottom plan view of a portion of an open umbrella.

FIG. 8 is a sectional view of the umbrella in partially collapsible position.

FIGS. 9, 10 and 11 are side views of various guy assemblies employable in the umbrella.

Referring to FIGS. 1—8, there is shown an umbrella 20 having a handle 22 and central post 24 to which the handle is joined. The post carries a plurality of long ribs 26 connected at one end to a ring 28 near the end 30 of the post. Intermediate shorter ribs 32 are connected between sliding cylinder 33 and intermediate points 35 of the longer ribs. Further intermediate ribs 34 are connected between the upper end of cylinder extension 37 and points 35 of the longer ribs. A fabric cover 39 is draped over the ribs 26 and secured thereto at opposite ends thereof. To the extent described, the umbrella is conventional.

According to the invention there is provided a plurality of holes 42 in the fabric cover 39 near the end of the post 24 and between ribs 26 as clearly shown in FIGS. 1, 2, 4 and 5. Over these holes is disposed a circular cap 40. The cap is a flat piece of fabric which is secured only at spaced points 43 to the ribs 26 by stitching or the like. Thus free passages for air exist underneath the unattached portions of cap 40 and through holes 42.

A plurality of guy assemblies 50 are provided for the

2

umbrella. Each guy includes a flexible cord or chain such as the beaded chain 52 shown in FIGS. 4—6, 8 and 9. At its outer end, each guy member is provided with a loop 53 whose ends are knotted and secured in a link

54. The loop is engaged on a spring ring 55. The ring 55 of each guy assembly is engaged on the beaded tip 56 mounted on the end of each rib 26. The other end of each guy member is formed with a loop 58 whose knotted ends are held by link 63. Loop 58 is engaged on the hooked end 59 of a U-shaped spring loop 60. The wider, round end 62 of the loop 60 engages around the post 24 above stationary ring 61. A plurality of loops 60 are thus arranged one above the other on ring 61 as clearly shown in FIGS. 4, 6 and 8. The guy members extend radially of post 24 and are stretched in tension when the umbrella is open as shown in FIG. 4. When the umbrella is closed the guy members are slack, as shown in FIG. 8. The guy members extend alongside of the rib assemblies 32, 34 and prevent the downwardly curved, tensioned ribs 26 from turning upwardly oppositely of their normal tensioned position when the umbrella is open. Thus the umbrella frame and cover are held against turning inside out in a high wind or storm. In addition, the air vents 42 release excess air pressure inside the concavity defined by the umbrella cover so that reversing of the ribs 26 and cover is prevented.

Instead of employing a beaded chain 52 with links 54 and 63 for engaging the loops 53 and 58, there may be provided a cord 52^a made of Fiberglas, nylon or the like, colored or uncolored as desired, as shown in FIGS. 7 and 10. The cord 52^a may carry a series of decorative, protective colored plastic or metal beads 75 as shown in FIG. 11. Crimped sleeves 51, 67 secure the loops 53^a and 58^a of the cords.

35 The guy assemblies can be quickly attached to any umbrella by snapping the rings 55 over the beaded tips 56 and by engaging the loops 60 on the post 24 above ring 61.

While I have illustrated and described the preferred 40 embodiments of my invention, it is to be understood that I do not limit myself to the precise constructions herein disclosed and that various changes and modifications may be made within the scope of the invention as defined in the appended claims.

45 Having thus described my invention, what I claim as new, and desire to secure by United States Letters Patent is:

1. A storm umbrella, comprising a frame with collapsible ribs secured at one end to a central post, a fabric 50 cover over said ribs, said cover being stretched tight and the ribs being bent down under tension when the frame is in open position, each of said ribs having a beaded tip, said cover having vents formed near said central post, and a fabric cap covering said vents and attached to the 55 cover at points spaced from the vents to permit free flow of air through the vents and between the cap and cover, there being a plurality of flexible guy members connected between the beaded tips and the central post, said guy members extending radially in tension out from the post 60 when the ribs and cover are tensioned, each of said guy members having a spring ring at one end and a generally U-shaped spring loop at the other end, said ring engaging over a beaded tip while the loop engages around the post.

2. A storm umbrella, comprising a frame with collapsible ribs secured at one end to a central post, a fabric cover over said ribs, said cover being stretched tight and the ribs being bent down under tension when the frame is in open position, each of said ribs having a beaded tip, and a plurality of flexible guy members connected between the beaded tips and the central post, said guy members 70 extending radially in tension out from the post when the

ribs and cover are tensioned, said central post having a stationary ring thereon, each of said guy members having a spring ring at one end engaged on one of the beaded tips and having a spring loop at the other end engaged on the post above said stationary ring.

3. A storm umbrella, comprising a frame with collapsible ribs secured at one end to a central post, a fabric cover over said ribs, said cover being stretched tight and the ribs being bent down under tension when the frame is in open position, each of said ribs having a beaded tip, and a plurality of flexible guy members connected between the beaded tips and the central post, said guy members extending radially in tension out from the post when the ribs and cover are tensioned, each of said guy members being a beaded chain terminating in two links, a first loop engaged in one of the links and secured on a spring ring, said spring ring being engaged on a beaded tip, a second loop engaged in the other of said links and held on a spring loop, the spring loop engaging on a stationary ring on the central post.

4. A storm umbrella, comprising a frame with collapsible ribs secured at one end to a central post, a fabric cover over said ribs, said cover being stretched tight and the ribs being bent down under tension when the frame is in open position, each of said ribs having a beaded tip, said cover having vents formed near said central post, and a fabric cap covering said vents and attached to the cover at points spaced from the vents to permit free flow of air through the vents and between the cap and cover, there being a plurality of flexible guy members connected between the beaded tips and the central post, said guy members extending radially in tension out from the post when the ribs and cover are tensioned, each of said guy members being a beaded chain terminating in two links, a first loop engaged in one of the links and secured on a spring ring, said spring ring being engaged on a beaded tip, a second loop engaged in the other of said links and held on a spring loop, the spring loop engaging on a stationary ring on the central post.

5. A storm umbrella, comprising a frame with collapsible ribs secured at one end to a central post, a fabric cover over said ribs, said cover being stretched tight and the ribs being bent down under tension when the frame is in open position, each of said ribs having a beaded tip, said cover having vents formed near said central post, and a fabric cap covering said vents and attached to the cover at points spaced from the vents to permit free flow of air through the vents and between the cap and cover, there being a plurality of flexible guy members connected between the beaded tips and the central post, said guy

members extending radially in tension out from the post when the ribs and cover are tensioned, each of said guy members being a cord having a loop at each end secured by a crimped sleeve, a spring ring engaged with one loop and a spring loop engaged with the other loop of the cord, the spring ring being engaged on one of the beaded tips, and the spring loop engaged over a stationary ring on the post.

6. A storm umbrella, comprising a frame with collapsible ribs secured at one end to a central post, a fabric cover over said ribs, said cover being stretched tight and the ribs being bent down under tension when the frame is in open position, each of said ribs having a beaded tip, and a plurality of flexible guy members connected between the beaded tips and the central post, said guy members extending radially in tension out from the post when the ribs and cover are tensioned, each of said guy members being a cord having a loop at each end secured by a crimped sleeve, a spring ring engaged with one loop and a spring loop engaged with the other loop of the cord, the spring ring being engaged on one of the beaded tips, and the spring loop engaged over a stationary ring on the post.

7. A storm umbrella, comprising a frame with collapsible ribs secured at one end to a central post, a fabric cover over said ribs, said cover being stretched tight and the ribs being bent down under tension when the frame is in open position, each of said ribs having a beaded tip, and a plurality of flexible guy members connected between the beaded tips and the central post, said guy members extending radially in tension out from the post when the ribs and cover are tensioned, each of said guy members being a cord having a loop at each end secured by a crimped sleeve, a spring ring engaged with one loop and a spring loop engaged with the other loop of the cord, the spring ring being engaged on one of the beaded tips, and the spring loop engaged over a stationary ring on the post, there being a plurality of decorative cylindrical beads on the cord protecting the same from wear.
